UNITED STATES PATENT OFFICE.

JOHN C. WAHL, OF CHICAGO, ILLINOIS, ASSIGNOR, BY MESNE ASSIGNMENTS, TO THE WAHL COMPANY, OF WILMINGTON, DELAWARE, A CORPORATION OF DELAWARE.

CALCULATING-MACHINE.

1,270,471.

Specification of Letters Patent. Patented June 25, 1918.

Application filed March 15, 1916. Serial No. 84,340.

To all whom it may concern:

Be it known that I, JOHN C. WAHL, a citizen of the United States, residing at Chicago, in the county of Cook and State of Illinois, have invented certain new and useful Improvements in Calculating-Machines, of which the following is a specification.

My invention is an improvement in calculating machines designed to perform vertical and horizontal additions and subtractions. The object of my invention is the provision of an improved calculating machine which will automatically add and subtract numbers as they are arranged in horizontal lines and simultaneously add them in vertical columns. Further, the object of my invention is to provide various interlocks and safeguards of operation to the end of guarding against accidental mis-operation of my improved machine by the operator.

Another object of my invention is the provision of improved connecting means between the vertical and cross totalizers which, when used in conjunction with my improved tabulating device, will prevent rebounding of the cross totalizer carriage when the same is intermittently connected to the typewriter carriage. These and other objects of my invention will be hereinafter described and claimed.

My invention is shown attached to a Remington typewriter which is provided with the usual set of letter keys, and therefore my machine may be used to compute numbers having alphabetic legends associated therewith.

My invention may be best understood by reference to the accompanying drawings, of which—

Figure 1 is a front view.

Fig. 2 is a side view.

Fig. 3 is a front view of the actuator with the covers removed.

Fig. 4 is a perspective of the operating mechanism, showing links joining vertical and cross actuators.

Fig. 27 is a perspective view of the cross gear shift lock.

Since the structure of my improved machine is complicated owing to the great variety of calculations which may be performed by it, I will divide the description of it into various chapters, dealing with particular portions of the machine in each.

In general my machine may be described

- as the machine disclosed in my issued Patent No. 893,719, plus a second actuator adapted to enter simultaneously into a second or cross totalizer the number entered into the 5 vertical totalizers shown in said issued patent. This second or cross actuator is controlled by gear shift devices which serve to determine the direction in which a number shall be entered into the cross totalizer.
- 10 These gear shift devices may be governed either manually by the operator or automatically by the motion of the typewriter carriage, on which are mounted the vertical totalizers, thus determining when each vertical 15 totalizer enters a zone of calculation how the number entered in said vertical totalizer shall be entered in the cross totalizer.

The typewriter.

- 20 The typewriter 30 is an ordinary Remington typewriter and is preferably equipped with a decimal tabulating mechanism of any suitable form. This typewriter is provided 25 with the usual set of letter keys 31 and a set of figure keys 32. All of the keys are connected to suitable type bars 33 which are adapted to print upon a platen 34 in the usual way. This platen is mounted upon a 30 carriage 35 which is given a tendency to travel toward the left by means of the usual spring tension device (not shown), and the travel of this carriage is controlled by reason of the fact that a rack 36 attached 35 to the carriage 35 gears into a pinion 37 rigid with a double escapement wheel 38. The rack 36 is not rigidly attached to the typewriter carriage, but is supported thereon by arms 39 pivoted on the carriage at 40, 40 and held in a position shown in Fig. 2 by a spring not shown. The escapement wheel 38 is given a tendency to rotate by the carriage spring, but such rotation is prevented by the escapement pawl 41 which is operated 45 by a pull rod 42 leading to a pull crank 43 mounted on the frame work. A universal bar 44, which extends beneath all of the typewriter keys 31 and the figure keys 32, is suspended from the crank 43 and is 50 adapted to be moved by any of said keys. Springs 45, each attached between the keys and the framework 29, serve to hold these keys, which are pivoted on a universal rod 46, in their normal position. De- 55 pression of any typewriter key, as for instance, the numeral key 32, will therefore result in printing the character associated with said key on the platen and actuating the escapement, thereby permitting the carriage 60 to escape one step to the left.

The typewriter 30 is equipped with tabulating mechanism of any suitable form. The particular tabulating mechanism which I have illustrated is the form commonly used 65 with the Remington typewriter, but I wish

to be understood that any other tabulating mechanism may be substituted for the form shown. The typewriter is equipped with a set of tabulating keys 47, Figs. 1 and 2, these keys being on the ends of rods 48, 70 which have their front bearing in the frame work 29 of the machine and their rear ends attached to tabulator stops 49, which are pivotally mounted on a shaft 50 rigid in the frame work 29. Each key 47 is associated with a tabulator stop 49. These stops are adapted to coöperate with a series of tabulating lugs 51 which are mounted on a slotted bar 52 mounted on the typewriter carriage. The lugs 51 are placed at a distance apart equal to the ordinary pitch of the typewriter, that is, one-tenth of an inch. These lugs in their normal positions are so placed on the bar 52 that they will not contact with any of the tabulator stops 49 when 80 it is operated by its associated tabulating key 47. However, in setting up the machine, certain of the lugs 51 are displaced to correspond with the particular set-up of the vertical totalizers. Then manipulation of 85 any tabulator key will release the typewriter carriage 35 from its escapement and said carriage will move to the left until stopped by contact of one of the lugs 51 with a protruding tabulator stop 49.

90 Each of the tabulator rods 48 is provided with a lug 53 adapted to contact with a bail 54, which is thus actuated by any of the tabulator keys 47. The bail 54 is supported from arms 55 which are pivoted on the 100 framework at 56. The arm 55 is joined by a push rod 57 pivoted on said arm at 58 to a crank arm 59 pivoted on the universal rod 46.

Rigid with the crank arm 59 is an arm 105 60, which is connected by a pull rod 61 to a rocking frame 62 pivoted in the framework at 63. Rotatably mounted in the framework 62 is a gear 64, which is adapted to be brought into engagement with the typewriter rack 36 when the frame 62 is tilted each time the typewriter carriage 35 is tabulated. Engagement of the gear 64 will raise the typewriter rack from engagement with the escapement pinion 37. This will of 110 course free the carriage from the escapement and said carriage will move to the left until arrested by the protruded tabulator stop. If it is desired to govern the motion of the carriage when the same is tabulated, a governor of any suitable form adapted to be actuated by the gear 64 may be attached to the typewriter. The slotted bar 52 has a tabulator lug 51 in each slot, and coöperating with these lugs is a pawl 65, pivotally 115 mounted at 66 in the upright post 67 mounted in the frame work 29. A spring 68 gives the pawl 65 a tendency to engage the lugs 51. However, a tail 69 on the pawl 65 contacts with an arm of the frame 62, (Fig. 25) 120 125 130

and serves to hold the pawl 65 out of engagement with said lugs 51 until the typewriter carriage is tabulated. Tilting of the frame 62 by means of the rod 61 will permit 5 the pawl 65 to come into engagement with the lugs 51 and to hold the typewriter carriage 35 securely against rebound when it has been arrested by a protruded tabulator stop 49. The necessity for preventing the 10 rebound of the typewriter carriage will be apparent from the description of the action of the cross actuator hereinafter to be described.

The vertical actuator.

15

The functions of the vertical actuator are:

1. Upon depression of any numeral key to operate certain universal members which 20 have functions which are necessary to the operation of any numeral key.
2. To perform certain universal operations in the totalizer.
3. To rotate the master wheel a number 25 of steps corresponding to the particular numeral key which is operated.
4. To lock the master wheel in its new position and return the universal parts to their normal positions.
- 30 5. To permit the spacing of the carriage to the next lower decimal place.

Connected to the above enumerated operations of the keys are several other functions, such as the single key mechanism, the object of which is to prevent the operation of 35 more than one key at a time, the full stroke mechanism which compels a full stroke of a numeral key when once a stroke is initiated, the truck lock which serves to lock the 40 typewriter carriage upon which the vertical totalizers are mounted immovably to the frame work during the depression of any key, and other functions hereinafter to be described.

- 45 45. Each of the keys 32 has connected to it a pull rod 70 (Figs. 1 and 2), which leads to a set of fans 71 which are rotatably mounted on a shaft 72 in the framework of the upper actuator. There is one of these fans 50 71 connected to each of the typewriter numeral keys. Each of said fans has on it a concentric cam surface 73 having a nose 74 and a heel 75 (Fig. 14). The nose 74 is adapted, upon rotation of the fan, to engage 55 with a roller 76 which extends the entire length of the upper actuator and which is adapted to be engaged by any of said fans 71 as they are rotated by their attached pull rods 70. The roller 76 is mounted on a rock shaft 77 by arms 78 and 79 (Figs. 4 and 14), and the rock shaft 77 is rotatably mounted in the framework 29 of the machine. On the rock shaft 77 is mounted the helical cam 80 serving to operate a shifter 81 slidably 60 mounted in the frame work. The rock shaft 65

operates in the following cycle upon depression of any key 32. The nose 74 of any of the actuated fans 71 first, as said fan is rotated in a counter-clockwise direction on depression of the key 32, contacts with the 70 roller 76 and thus rotates the rock shaft 77 in a clockwise direction. This continues until the roller 76 has reached the concentric surface 73 of the fan 71. The rock shaft 77 is therefore held stationary during the 75 travel of the fan through the angle embraced by the nose 74 on one side and the heel 75 on the other. As the rotation of the fan 71 continues, the rock shaft 77 which is under spring tension (in a manner hereinafter to 80 be described) escapes from the heel 75 and snaps back to its normal position as shown in Fig. 14. Upon the upstroke of the key, the heel 75 of the fan 71 engages the roller 76 and rotates the rock shaft 77 in a counter-clockwise direction. Following this engagement there ensues a period of no motion of the rock shaft corresponding to the engagement of the cam 73 with the roller 76, and upon the fan reaching its normal 90 position shown in Fig. 14, the rock shaft 77 snaps to its normal position co-incident with the arrival of the fan 71 to its normal position, which is co-incident with the return of the typewriter numeral key 32 to its normal 95 position.

To sum up this motion of the rock shaft,—on the down stroke of the typewriter key, it is first rotated in a clockwise direction through a certain angle, then follows a period of rest, and then a quick return to its normal position. On the upstroke of the key the rock shaft is rotated through an angle in the contrary direction, then follows a period of dwell, and then an 100 escapement of the rock shaft to its normal position co-incident with the arrival of the typewriter key in its normal position. The object of these various motions of the rock shaft will be hereinafter described. 110

Rotatably mounted in the framework of the machine is a sector shaft 82 upon which is mounted a series of arms numbered 91 to 99 both inclusive, by means of which said sector shaft 82 may be rotated. Rotatably 115 mounted on the shaft 72 is a set of goosenecks 83, there being a gooseneck 83 associated with each fan 71. Rigidly mounted in each gooseneck is a pin 84 which is adapted to be engaged by the edges of an opening 85 120 in each fan 71. As said fan is turned by the depression of a key 32 the rock shaft 77 will first be rotated through an angle by the nose 74 after which a side of the slot 85 will contact with the pin 84 and thereafter rotate 125 the associated gooseneck with the fan 71 during the time when the roller 76 is on the concentric portion of the cam 73. On each gooseneck is a cam surface 86, which is adapted to contact with and rotate a roller 130

- 87 mounted in each of the arms 91 to 99 inclusive. Engagement of the cam 86 with the roller 87 will therefore rotate the sector shaft 82 until the roller 87 reaches a concentric slot 88 which is in each gooseneck. Further rotation of a gooseneck will therefore serve to maintain the sector shaft in its then displaced position. The arms 91 to 99 inclusive are spaced on the sector shaft 82 in spiral arrangement, the arm 91, for instance, being so spaced that when said arm is operated by its associated gooseneck 83, the sector shaft 82 will be rotated the space of one unit. When the roller 87 mounted in the arm 92 is engaged by its associated gooseneck 83, the sector shaft 82 will be rotated a space of two units, and so on.
- To sum up what has gone before, depression of any typewriter key will first result in the rotation of the rock shaft 77 through a certain angle, then, during the time occupied by the roller 76 on the concentric part of the cam 73, the sector shaft 82 will be rotated through an angle which is proportional to the number key which has been operated. At the completion of the down stroke of the key, the rock shaft 77 will return to its normal position, due to the fact of the roller 76 escaping from the heel 75. However, since the fan 71 is still displaced, the sector shaft 82 will remain in its displaced position, the roller 87 being held in the concentric slot 88 of the particular gooseneck operated.
- I will now describe the mechanism by means of which this differential motion of the sector shaft 82 is communicated to a master wheel. Reference, particularly to Figs. 3, 14 and 15, will disclose that a block 89 is rigidly mounted on the sector shaft 82. Pivoted to this block by a bolt 90 is a sector 101, the above described mounting having for its object to render the sector rigid to the shaft 82 as far as rotation is concerned, but transversely movable thereto owing to the fact of the sector being pivoted on the bolt 90. The sector 101 is embraced by a slot 102 in the shifter 81, which is reciprocatingly mounted in the framework. A second slot 103 is engaged by the helical cam 80 rigid on the rock shaft 77. The sector 101 is adapted to mesh with either a gear 104 or a gear 105 according to the position of said gears as determined by a gear shaft arrangement hereinafter to be described. However, the sector when at rest is out of mesh with both said gears, being in a tilted position in respect to the sector shaft 82. The preliminary motion of the rock shaft ensuing upon the first part of the down stroke of the key, by means of the helical cam 80 shifts the shifter 81 to the left, thereby bringing the sector 101 in a position at right angles to the sector shaft 82. When in this position the sector may be in mesh either with the gear 104 or the gear 105, as determined by the gear shift device. Upon rotation of the sector shaft 82 by the particular gooseneck which is associated with the operated fan 71, a motion will be communicated by the sector 101 to the gear 104 or 105, which at that time happens to be in mesh therewith, and this rotation will be proportional to the displacement of the sector shaft 82, which in turn is proportional to the particular numeral key which has been operated.
- It will be remembered that upon the completion of the down stroke of the key 80 the rock shaft 77 instantly returns to its normal position. This will result in rotation of the helical cam 80 to its normal position, and the return of the shifter 81 and the sector 101 associated therewith to their corresponding normal positions, as shown in Fig. 3. Upon the back stroke of the key 80 the sector shaft 82 will be rotated, owing to the return of the gooseneck in engagement with said sector shaft 82 to its normal position, yet this backward rotation will not be communicated to the gear 104 or 105 since the sector 101 will be out of mesh with either of said gears on its back stroke.
- I will now describe the means by which motion of the gears 104 or 105 is communicated to a master wheel. The vertical master wheel 106 is rigidly mounted on a shaft 107 which turns in the framework. Slidably, but non-rotatably, mounted on said shaft is the gear 104 before referred to. In the hub of this gear is a groove 108 engaging in which is a stud 109 mounted in a lever 110, which is pivoted at 111, in a post 112 mounted in the frame work 29. The gear 105 is rotatably mounted on a rod 113 which is slidably mounted in the frame work. The gear 105 (Fig. 17) has in it a groove 114. A stud 115 mounted on the lever 110 engages this groove and serves to transmit motion of the gear shift rod 113 (Fig. 17) to the gear 104. In one position of the gear shift rod 113, the gear 104 is in a position to be engaged by the sector 101 when the same is operated by the rock shaft 77. This corresponds to the subtraction position of the vertical actuator, and is the position shown in Fig. 3. When the gear shift rod 113 is moved to a second position the gears 104 and 105 are in line with each other and the sector 101 will engage neither of them when the sector shaft 82 is operated. This corresponds to a disconnect position of the vertical actuator. When the gear shift rod 113 is in a third position, the gear 104 is moved into the path of the sector and the gear 105 is moved into a position in which the sector will not engage said gear. This position corresponds to the addition position of the vertical actuator.

cal actuator. Obviously the system comprising the two gears 104 and 105, the lever 110 which connects these gears, and the rod 113 constitutes a gear shift device and 5 serves to transmit the motion of the sector 101 to the master wheel 106 in a manner determined by the position of said rod 113.

Having described the gear shift arrangement, I will now describe universal motions which take place before and after a rotation of the master gear. These universal motions occur upon the actuation of any figure key 32 and are therefore motions which occur or take place each time a digit 10 is put into a totalizer.

The first one of these motions is the motion which operates the master dog, this dog serving in a manner hereinafter to be described to perform certain operations in 20 the totalizer, and also to lock the truck carrying the totalizer rigid with the frame of the machine during the insertion of a number. The rock shaft 77 has rigid with it a crank arm 116 which serves to actuate 25 a link 117 pivoted at 118. The upper end of this link has in it a slot 119 which engages a pin 120 mounted in a master dog cam 121 which is rotatably mounted in the frame work on a shaft 122. A master dog 30 123 is rotatably mounted in the frame work on a shaft 124, and has a horizontally extending portion 125 which serves the purpose of a truck lock, and a vertical arm 126 which operates upon the swinging arms of 35 the totalizer as hereinafter to be more specifically described.

Mounted on the master dog 123 is a roller 127 which is engaged by a cam surface 128 in the master dog cam 121. Rotation of the rock shaft in a clockwise direction, Fig. 14, will result in upward motion of the link 117 and consequent rotation of the master dog cam 121 in a clockwise direction. The action of the cam surface 128 40 on the roller 127 will rotate the master dog 123 in a counter-clockwise direction, the vertical arm 126 serving to lift the swinging arms of the totalizer in a manner hereinafter to be described, and the truck lock 45 125 to engage between the teeth of a rack 129 rigidly mounted on the vertical truck 130 which serves as a support for the vertical totalizers. From the immediately preceding description, it will be apparent 50 that depression of any numeral key 32 will ultimately result in a counter-clockwise rotation of the master dog 123 and the consequent locking of the truck 130 to the typewriter frame during the time when the 55 truck lock 125 is between the teeth of the rack 129. This motion of the master dog 123 takes place during the first part of the down stroke of the key. Following this motion comes the differential rotation of the 60 master wheel 106, and then as the rock 65

shaft escapes from the heel 75 of the cam 73, the master dog suddenly returns to its normal position and the carriage 35 then escapes to the next following decimal place.

Another universal motion is the motion of the master pawl, this pawl serving to definitely align the master wheel in its position during the time when said wheel is not being rotated by a depression of the keys. 70

Inspection of Fig. 4 will show that the rock shaft 77 has on it a crank arm 131, in which is mounted a pin 132. As the rock-shaft is rotated in a clockwise direction the pin 132 will encounter the cam surface 133 80 of the master pawl 134, which is mounted on a shaft 135 pivoted in the frame work. The pawl 134 is provided with a nose 136 which is adapted to enter between and align the teeth of the master wheel 106. The preliminary motion of the rock shaft will rotate the master pawl 134 out of engagement with the master wheel 106, leaving said wheel free to rotate. Upon the completion of the down stroke of the key, and coincident with 90 the return of the rock shaft 77 to its normal position, the master pawl 134 will return to its position of engagement with the master wheel 106. A spring 137 (Fig. 14) one 95 end of which is attached to the master pawl 134, and the other end to the frame work of the machine, serves to maintain the master pawl in contact with the teeth of the master wheel 106.

Another universal motion which takes 100 place upon the depression of any numeral key 32 is that of the full stroke mechanism. Reference to Fig. 14 will disclose that each one of the fans 71 is provided with a set of ratchet teeth 138 and 139, these teeth pointing in opposite directions. A shaft 140 has mounted on it a down full-stroke pawl 141 extending the entire length of the vertical actuator. This pawl is adapted to contact with any of the teeth 138 and thus prevent 105 the direction of motion of the numeral key being reversed upon the downstroke thereof. The pawl 141 has rigidly attached thereto a piece 142 having a cam 143 adapted to contact with and be rocked by an arm 144 rigidly attached to the rock shaft 77. When the rock shaft 77 is in its normal position, the parts are in the position shown in Fig. 14, and the full stroke pawl is in a position to engage the ratchet teeth 138 on any one 110 of the fans 71. When the rockshaft is thrown to its forward position upon the completion of the down stroke of the key, the arm 144 rotates an arm 145 which is rigidly attached to a shaft 146 on which is 115 mounted the up full-stroke pawl 147. This pawl 147, like the pawl 141, extends the entire length of the actuator and is adapted to contact with the teeth 139 upon any of the fans 71. In consequence, upon the preliminary 120

125 130

nary motion of the rock shaft 77, the pawl 147 is rotated in a counter-clockwise direction, Fig. 14, and therefore does not interfere with the motion of the fan 71, for the reason that the point of the pawl 147 is thrown out beyond the teeth 139. On the down stroke of the key, the down full stroke pawl 141 is the only one which is in action, and this pawl prevents an upward motion of the key until the completion of the down stroke. When the numeral key 32 reaches the bottom of its down stroke, the rock shaft 77, as before noted, returns to its normal position. At this time, both the full stroke pawls 141 and 147 are in position to engage their coöperating teeth 138 and 139. However, upon the beginning of the upstroke of the key, the heel 75 of the fan 71 engages the roller 76 as before noted, and rotates the rockshaft 77 in a counter-clockwise direction. This results of course in the rotation of the arm 144 rigid in the rock shaft and its lifting of the down full stroke pawl 141 out of the way of the teeth 138 and permits the spring 148 which extends between the down full stroke pawl 141 and the up full stroke pawl 147 to bring said pawl 147 into contact with the teeth 139. These teeth prevent the downward motion of the key 32 until the upward motion has been fully completed or until the roller 76 has escaped from the nose 74 of the cam 73 on the fan 71. The rockshaft then returns to its normal position and the parts are in position for a second downstroke of the key.

It will be apparent that the full stroke mechanism just described is for the purpose of preventing an incomplete stroke of any numeral key 32. When once a motion of any of these keys has been initiated the motion must be completed to the end of the down stroke and then to the end of the upstroke before the motion of any other key may be initiated. This full stroke mechanism is of great value in preventing faulty manipulation of the machine.

Another universal motion which takes place in the vertical actuator is that of the single key mechanism which has for its object the prevention of the operation of more than a single key at one time.

Referring particularly to Figs. 5, 14, and 15, it will be seen that each of the fans 71 has a nose 149 which is adapted to engage the single key cams 150. These cams are rotatably mounted in the frame work on small shafts 151, and each end of the series of cams 150 is constrained against the frame work 29 so that in the whole series there shall be a vacant space the width of any one of the fans 71. Upon rotation of any fan by reason of depression of a typewriter numeral key 32, the nose 149 will enter between two of the cams 150 and this

will take up all the lost room between the series of cams and the frame work. The operation of a second key while one key is down will be prevented since the nose 149 of the second operated fan 71 will be unable to force its way between its two contracting cams 150.

I will now describe the means by which the rock shaft 77 is held in its normal position. Pivoted on the frame work at 152 and 153, (Fig. 16), are the rock shaft locating arms 154 and 155. These arms are held by a spring 156 in contact with the stud 157 mounted in the frame work. The roller 76 attached to the rock shaft 77 contacts with both arms 154 and 155. When the rock shaft is rotated in a clockwise direction, the arm 154 will be displaced and the spring 156 will tend to restore the rock shaft to its normal position. On the back stroke of the key when the rock shaft is rotated in a counter-clockwise direction, the arm 155 will contact with the roller 76, and the spring 156 will tend to bring said rock shaft into its normal position. It will thus be seen that the rock shaft 77 may be rotated in either direction from its normal position and the spring 156 will always tend to bring said shaft to its normal position, as shown in Fig. 16.

In order to bring together all of the various operations given in the previous description of the upper actuator, I shall now describe the cycle of the actuator parts ensuing upon the depression of any numeral key, for instance, the 9 key, assuming that 9 is to be put into the totalizer in addition.

Upon the first part of the depression of the key, the rock shaft 77 is rotated in a clockwise direction by the action of the nose 74 of the fan 71 associated with the 9 key. This rotation of the rock shaft 77 is resisted by the spring 156 and results,

1st, In the withdrawing of the nose 136 of the master pawl 134 from the master wheel 106, and

2nd, In the rotation of the master shaft 124 in a counter-clockwise direction, Fig. 14, thereby locking the truck 130 carrying the vertical totalizers rigid to the frame work and by means of the vertical arm 126 performing certain operations in the totalizer.

3rd, In the nose 149 of the fan 71 entering between the single key cams 150, thereby preventing the operation of any other numeral key.

4th, In the withdrawal of the full stroke pawl 147 from a position to contact with the teeth 139, thereby permitting further rotation of the fan 71.

5th, In the helical cam 80 shifting the sliding plate 81, thereby bringing the sector 101 in mesh with the gear 104.

6th, Another universal motion that occurs

- upon the depression of any key is the action of the supplemental alining pawl 158. Since the action of this pawl is exactly like the action of the pawl 56 in Fig. 3 of my 5 issued Patent #1,148,733, August 31st, 1915, it is unnecessary to describe this action herein. The object of this supplemental alining pawl is to assist in removing the spiral effect from the totalizer.
- 10 At the time the preliminary motion of the rock shaft has been completed, that is, when the roller 76 has reached the dead surface of the cam 73, the slot 85 in the fan 71 has contacted with the pin 84 in the gooseneck 15 associated with the 9 key.
- Further depression of the 9 numeral key 32 results in further rotation of the fans 71 and the slot 85 comes in contact with the pin 84 thereby operating the one of the 20 goosenecks 83 which rotates the sector shaft 82 the distance of 9 spaces. This rotation of the sector shaft is communicated by the sector 101 to the gear 105 and by said gear to the master wheel 106. When the key 32 reaches the bottom of its down stroke, the roller 76 escapes from the heel 75 of the cam on the fan 71 and the spring 156 at once snaps the rock shaft back to its normal position. This results in the shifter 81 25 withdrawing the sector 101 from the gear 105 and the unlocking of the truck 130 by reason of the return of the master dog 123 to its normal position. It also results in the reengagement of the master pawl 134 30 with the master wheel 106. The sector shaft 82, however, remains in its displaced position due to the engagement of the roller 87 in the concentric slot 88. The 9 key now starts on its return to its normal position 35 by reason of the action of one of the springs 45, and the rock shaft is now rotated in a counter-clockwise direction by reason of the action of the heel 75 on the roller 76. This results in the withdrawal of the down full 40 stroke pawl 141 from contact with the teeth 138 and the engagement of the upper full stroke pawl 147 with the teeth 139. As the key returns to its normal position, the gooseneck 83 is returned to its normal position 45 and the sector shaft is returned to its normal position due to the tension of a spring 159 extending between the frame work and the sector shaft returns said shaft to its normal position.
- 50

55 *The cross actuator.*

The cross actuator in its relation to the vertical actuator is shown in Fig. 3. Reference thereto will disclose that the cross actuator is located to the right and somewhat below the vertical actuator. The cross actuator is intended to be operated at the same time as the vertical actuator and by the depression of a single key since, as will be

hereinafter pointed out, a large number of 65 operations are to be performed with my machine involving the simultaneous entry of a number into both a vertical and the cross totalizer. It will not be necessary to go into an extended description of the cross 70 actuator since a large number of its parts are substantially duplicates of the vertical actuator.

In Fig. 4 is shown a perspective view of the connection between the two actuators. 75 The cross actuator is provided with a rock shaft 160 and a sector shaft 161, these two shafts being similar in function to the rock shaft 77 and the sector shaft 82 of the vertical actuator. A parallelogram link connection between the two shafts insures their moving in synchronism. This link connection may be described in detail by noting that (Fig. 4) the sector shaft 82 has rigidly attached thereto a crank arm 162 and the 80 sector shaft 161 has rigidly attached thereto a crank arm 163. These crank arms are of equal length and are set parallel to each other. A link 164 serves to connect the two arms and since the crank arms 162 and 163 85 are equal and parallel, the motion of the vertical sector shaft 82 will be exactly reproduced by the cross sector shaft 161. The rock shafts 77 and 160 are connected in a similar manner. A crank arm 165 is rigid to the rock shaft 77 and the crank arm 166 is rigid to the cross rock shaft 160. These crank arms are equal and placed on their respective shafts so as to be parallel to each other. A link 167 serves to connect the two 90 arms and since the crank arms 165 and 166 are equal and parallel, the motion of the rock shaft 77 is exactly reproduced by the rock shaft 160. The sector shaft 161 has mounted thereon a sector 168 95 which is similar to the sector 101 of the vertical actuator. The motion of this sector is controlled by the helical cam 169 which controls a shifter 170, these parts being similar to the corresponding parts of the vertical actuator. The sector 168 is adapted to 100 engage either the gears 171 or 172, these gears corresponding in position and function to the gears 104 and 105 of the vertical actuator.

Pivoted in the frame work 29 on a post 115 173 (Figs. 10 and 17) is a bar 174 which has the same function in respect to the gears 171 and 172 as the bar 110 has to the gears 104 and 105 of the vertical actuator. By means of either the gear 171 or the gear 172, 120 motion of the sector is communicated to the cross master wheel 175, and this master wheel serves to transmit the motion as determined by the numeral key into the cross totalizer. Obviously this motion will be 125 transmitted either in addition or subtraction accordingly as the sector 168 engages the gear 172 or the gear 171. The position of

these gears is determined by the position of the cross gear shift rod 176. The position of this rod is controlled by the gear shift mechanism which will be hereinafter described in a special chapter. It will suffice for the present to say that the gear shift rod 176 may occupy any one of three positions, thereby determining that the master wheel 175 of the cross actuator shall rotate to determine addition or the master wheel 175 shall not rotate at all or shall rotate in a direction to determine subtraction, these rotations, it is assumed, occurring in consequence of the operation of any of the numeral keys 32. Operation of this rod 176 is precisely similar to that of the gear shift rod 113 of the vertical actuator. Both, by their positions, serve to determine first, whether or not a number should be inserted in their associated totalizers and second, if the number is inserted, whether such number should be inserted in addition or subtraction.

The cross actuator is also provided with a master dog 177 (Fig. 9) and a master pawl 178, these two members being controlled by the rock shaft 160 in precisely the same way as the master dog 123 and the master pawl 134 of the vertical actuator. These two parts have the same function on their associated master wheels and cross totalizers as the corresponding parts have upon the master wheel and totalizers of the vertical actuator. It will therefore not be necessary to herein insert an extended description of their operation.

At this point it will possibly be worth while to recapitulate in a general way the operation of the previously described mechanisms. We have started with the numeral key and traced the action of said key into producing differential rotation of the vertical master wheel 106 and the cross master wheel 175. We have also seen how depression of the key produces certain universal actions, that is, the single key mechanism, the full stroke mechanism, the master dog, and master pawl actions. The master dog and master pawl actions are repeated in the cross actuator, since they are necessary, the one to operate on the cross totalizer and the other to operate on the cross master wheel 175. However, the full stroke and single key actions are not necessary to the cross actuator since controlling the action of the key in these respects from the vertical actuator will be sufficient.

We have also seen that the motion of the vertical master wheel 106 and the cross master wheel 175 is controlled by the position of the gear shift rods 113 and 176, these rods determining each for its associated master wheel whether or not said master wheel shall rotate to produce addition, to produce subtraction, or not rotate at all,

this latter case corresponding to the operation of a number's being simply copied out of the totalizer without withdrawing it.

The totalizers.

The vertical totalizers 179, 180, 181 and 182 are mounted slidably on a truck 130. This truck is supported by a roller 183 which is mounted on a shaft 184 which rotates in a bearing 185 inserted in the framework 29 of the machine. A roller 186 turning on a stud 187 serves to maintain the section 188 of the truck 130 in contact with the side of the roller 183. Thus, the lower side of the truck 130 is completely constrained by these two rollers. The upper side of the truck 130 has formed on it an upwardly projecting flange 189, which contacts with a roller 190 rotatably mounted in a bearing 191 in the frame work 29. The axes of the rollers 190, 183 and 186 are in the same plane as the master wheel 106. Thus, the truck 130 is supported in practically one line in the plane of the master wheel 106 and is free to have a slight vertical or horizontal movement at the ends thereof. This results in the totalizers which are mounted on the truck being brought into exact alinement with the master wheel 106 since the rollers constrain the truck in the plane of said master wheel. However, since the truck is free at the ends and may have some slight motion in respect to its connections to the typewriter carriage, the necessity for maintaining absolute parallelism between the truck 100 bearings and the bearings of the typewriter carriage is avoided.

The truck 130 has mounted thereon arms 192 and 193, Fig. 1, these arms being adjustable by means of screws 194 and 195 respectively. Angled pieces 196 and 197 are attached to the carriage 35 of the typewriter and screws 198 and 199 serve to connect the arm 192 to the piece 196 and the arm 193 to the piece 197. The holes in the arms 192 and 193 are oblong for the purpose of permitting some slight relative motion between the truck 130 and its connection to the typewriter carriage 35. Since the typewriter carriage escapes step by step upon the action of the numeral keys, the truck 130 will by means of the above recited connections be advanced step by step also. The truck 130 has in its forward side, Fig. 14, dove-tail sections 200 and 201, these sections serving to form a sliding support for the vertical totalizers.

The totalizer wheels are mounted between the two side plates 202 and 203, Figs. 1, 3 and 14, in which are dove tails 204 and 205 to fit with the dove tail sections 200 and 201 of the truck 130. A rack 206 is fastened to the truck and has teeth corresponding to the pitch of the typewriter escapement rack 36. This pitch is usually $\frac{1}{3}$ of an inch, that is, 130

ten teeth to the inch, although any other pitch may be used if the spacing of the totalizers is accordingly changed. The totalizer is held in its position by a latch 208, 5 (best shown in Fig. 14) mounted on the shaft 209 pivoted in the side plates 202 and 203 and is held in contact with the truck 130 by a spring 210 which extends between a stud 211 in the latch 208 and a stud 212 10 in the plate 202. On the forward end of this latch is a finger piece 213 which serves to operate the latch 208. The rear portion of the latch has a hook 214 adapted to engage the dove tail section of the truck 130 15 and a tooth 215 which enters the teeth of the rack 206 and thereby prevents the lateral motion of the totalizer as a whole. The hook 214 serves to locate the dove tail in the bottom of the totalizer side plates firmly 20 against the dove tail section of the truck 130, and the tooth 215 prevents lateral movement. Thus the totalizer is held securely 25 against motion relative to said truck. The totalizer side plates 202 and 203 serve as supports for shafts 216, 217, 218, 219, 220, 221, 222 and 223. The shaft 219 which is rigidly connected to the side plates serves as a support for the totalizer carrying wheels 224 which are rotatably mounted on said 30 shaft. These wheels are provided with 30 gear teeth 225, a locking disk 226, having three passing scallops 227, and three carrying teeth 228. In the plane of the teeth 225 is an idler gear 229 rotatably mounted on the shaft 220, and which serves to communicate the motion of the carrying wheel 224 to a 35 gear 230 which is rigid with a totalizer number wheel 231, rotatably mounted upon the shaft 221. The carrying teeth 228 engage 40 the gear 232 which is mounted on a stud 233, carried in a swinging arm 234, which is free to turn upon the shaft 216.

Rigid with the gear 232 is a star wheel 235 which is in the same plane as the locking 45 disk 226, the passing scallops 227 permitting one step motion of this star wheel 235 whenever the same shall have been actuated by the engagement of the carrying teeth 228 with the gear 232. At other times the star 50 wheel 235 is held locked against motion owing to the engagement of the concave portions of the star wheel with the round surface of the locking disk 226. Rigid with the star wheel 235 and the gear 232 is a third 55 gear 236 which serves to transmit the carrying of the gear 224 to the gear 224 in the next higher decimal place.

The carrying chain just described will be 60 recognized as the well-known locked Geneva gear chain. Since numbers are inserted in the totalizer at any decimal place, it becomes necessary to provide some way of unlocking the chain at the actuated point. This is accomplished by the expedient of mounting 65 the gears 232, 235 and 236, not on a rigid

shaft, but upon the swinging arm 234, which is rotatably mounted on the shaft 216, and held in its position by a spring 237 extending between the arm 234 and the shaft 222, rigid in the frame work.

In the bottom of the arm 234 is a slot 238, Fig. 14, on the front part of which is a projection 239, which is adapted to be engaged by the surface 240 of the vertical arm 126 of the master dog 123. The angle 70 of throw of the master dog 123 is so proportioned that when said dog is actuated upon the preliminary motion of the keys, the surface 240 comes into approximately a vertical position. The swinging arm 234 is therefore 75 lifted and the gears 232, 235 and 236 are lifted bodily out of engagement with the carrying wheel which is in engagement with the master wheel and the carrying wheel of next lower order. This unlocks the Geneva 80 chain at the actuated point and there then exists in the totalizer a locked counting chain extending from the master wheel to the highest wheel of the totalizer.

Mounted between the totalizer side plates 90 is a bar 241 which enters slots 242 in the star wheel 235 when the latter is lifted by the swinging arm 234. This bar 241 serves to hold the star wheel 235 and its associated gears in a correct position during the disengagement of these gears with their associated 95 carrying wheels 224.

I shall hereinafter term the assemblage of gears 232, 235 and 236 a "transfer gear", since the function of this gear is to transfer 100 the tens from one denomination to another.

Owing to limitations of space, the carrying wheels 224 being but 1/10 of an inch apart, it is necessary to stagger the transfer gears. There is one set of transfer gears 105 which is mounted on the swinging arms like 234. The alternate transfer gears are similarly mounted on swinging arms like 243, which are rotatably mounted on the shaft 217, and are held in their correct position 110 by springs 244 extending between said arms and the shaft 218 supported between the totalizer side plates 202 and 203. It is to be understood of course that there is a plurality of arms 234 and 243 and that I have 115 given common numbers to each of the arms in the plurality. Both sets of arms terminate in cam surfaces 245 which serve to actuate a safety bar 246, which is pivotally mounted in the frame work on the shaft 223. 120 This safety bar 246 extends the entire width of the totalizer and is adapted to be turned when any of the arms 234 or 243 are actuated by the master dog. A portion 247 extends in the path of all the cams 245 and 125 the locking portion 248 is adapted to be brought into the path of the locking surfaces 249, which is present on all of the swinging arms 234 and 243. The function of the safety bar is to securely lock all of 130

the transfer gears into mesh with their associated carrying gears when one of the transfer gears is raised out of mesh to permit actuation of the totalizer at any desired point.

- 5 The transfer gears which are mounted on the arms 243 are similar to the gears mounted on the arms 234 and their star wheels are similarly locked on the bar 250 which extends between the side plates of the totalizer.
- 10 The latch 213 has on it a cam 251 which is adapted to engage the safety bar 246 and rotate this bar into a position to lock all of the swinging arms 243 and 234 whenever the totalizer is taken off of the truck. It will be obvious that removal of the totalizer will result in a rotation of the latch 208 about its shaft 209 by the spring 210, whereupon the safety bar 246 will be rotated so as to bring the locking portion 248 into a position 15 to prevent motion of any of the arms 243 or 234. The swinging arm 243 in the lowest decimal place of the totalizer does not have a transfer gear mounted upon it, but instead has mounted on it a units lock 252 which 20 serves to hold the units wheel of the totalizer in a locked position. The units lock is of course raised out of mesh with the carrying wheel 224 in the units place of the totalizer by the master dog 126 whenever the said 25 wheel is actuated by the master wheel.

30 The vertical totalizer 179 is provided with a suitable cover 253 in which is a window 254, through which the numbers on the numeral wheels are visible. From the description just given, it will be apparent that the totalizer is adapted to have numbers inserted in it at any decimal place and that the cycle of a number insertion is as follows:

First, the totalizer 179 is mounted on the 40 truck 130 which travels with the typewriter carriage and the master wheel 106 is rotatably mounted in the frame work of the machine, therefore the totalizer will progress relatively to said master wheel, which will 45 engage the totalizer carrying gears 224, one after the other, coming first into engagement with the carrying wheel in the highest decimal place of the totalizer. Upon the depression of the numeral key, the transfer 50 gear connecting the engaged wheel 224 with that of lower order will be bodily lifted out of mesh and then the differential rotation of the master wheel will follow. Since the transfer gears connecting the actuated carrying gears 224 to those of higher order will 55 remain in mesh, there will exist a locked carrying chain extending from the then actuated carrying gear 224 to the highest wheel of the totalizer. After the differential 60 rotation of the master wheel has been completed, the master dog 123 will snap back to its normal position as described in connection with the description of the actuator, this will restore the displaced transfer

gear and also unlock the truck and the typewriter will progress to the next decimal place, in which the operation will be repeated.

I have described the totalizer 179 in detail. The other vertical totalizers and the 70 cross totalizer are similar to the totalizer 179 and therefore need not be further described.

The cross totalizer.

75

The cross totalizer 255 is similar in construction to the vertical totalizers 179, 180, 181 and 182. It is mounted on a cross truck 256, which is similar in section to the vertical truck 130. A locking plate 257 is attached to the cross truck 256, and is provided with a suitable notch to receive the latch 258 of the cross totalizer, thus serving to hold the cross totalizer in a proper position on a cross truck 256. The cross totalizer 255 is provided with an index plate 259 having marks thereon, which are read in connection with the mark 260 on the front of the cover of the cross actuator.

The bearings for the cross truck are in 90 a casting 261, which is supported from the frame work by the plates 262 and 263. The casting 261 is provided with two V-shaped channels 264 and 265 and the cross truck also is provided with two V-shaped grooves 266 95 and 267. These grooves form the raceways for a set of balls 268 which are constrained by a suitable retainer 269 in the upper edge of which is cut a rack 270 which meshes in the pinion 271 rotatably mounted on a stud 272 in the casting 261. A rack 273 is cut on the upper edge of the cross truck 256, and meshes in with a gear 274 rigid with and of twice the number of teeth of the pinion 271. The retainer 269 is thus given a velocity of 100 one-half the velocity of the cross truck 256, and the balls are maintained in their proper positions.

The cross truck 256 is given a tendency to 110 return to the right (Fig. 10) by a spring 275 which has one end fastened to a stud 276 in the casting 261, and the other end fastened to a stud 277 in the cross truck 256. The spring 275 passes over a roller 278 mounted on a stud 279 in the casting 261. 115

The cross truck 256 is provided on its lower side with a rack 280 in which are teeth 281 located 1/10 of an inch apart. The master dog 177 located in the cross totalizer, enters these teeth 281 and locks the cross totalizer during the actuation of any numeral key in the same manner as the vertical truck 130 is locked by the action of the truck lock 125 upon the rack 129.

The normal position of the cross truck 256 125 is determined by the contact of a plate 282 with a lever 283 pivoted in the frame work at 284, and adapted to have its upper end

contact with the plate 262. The plate 282 is provided with a series of notches 285 which are located upon studs 286 in the cross truck. The plate 282 is held on the cross truck by screws 287, this plate being provided with a series of tapped holes 288. The plate 282 is made adjustable to accommodate the use of various widths of cross totalizers upon the cross truck 256. It will 5 afterward be described how the cross truck 256 is released from the vertical truck 130 at a constant predetermined position, which is when both trucks have reached a position in which their respective totalizers 179, 180, 181 10 and 182, and the cross totalizer 255, are one space to the left of the vertical master wheel 106 and the cross master wheel 175. The normal position of the cross truck 256 is determined by the position of the plate 20 282 and this plate is provided with a series of numbers 291 (of which but one is shown), these numbers signifying the different widths of cross totalizer corresponding to a given location of the plate 282. The numbers 291 are visible through a hole 292 in the casting 261.

When the cross truck is not in use, it may be pushed to the extreme left of its travel and there held in position by a latch 293 30 (Figs. 5 and 13) pivoted on a stud screw 294 in the under side of the casting 261. The latch 293 is provided with a nose 295 which is adapted to project into the path of the cross truck 256 when the latter is pushed to its 35 extreme right hand position. A snap spring 296, in conjunction with a stud 297 on the casting 261, which engages with locating holes 298 and 299 in the latch 293 serves to maintain the latch 293 in either of its positions.

The connecting means between the vertical and cross trucks.

The function of the connecting means is 45 to provide a plurality of reciprocations of the cross truck during one travel of the vertical truck. There are also means to prevent or guard against the cross truck being displaced from its normal position. The connection between the two trucks is perhaps best shown in the perspective view of Fig. 22 and the detail view of Fig. 26.

Reference to Fig. 16 will disclose that on the right side plate 203 of the vertical totalizers is a heel 300, which is adapted to engage the hook 301 (Fig. 22) on the pickup beam 302. A bracket 303 fastened to the cross truck 256 has in it a slot 304 (Figs. 10 and 22) which serves as a guide for a stud 60 screw 305 rigid in the pickup beam 302. Between a stud 306 and the bracket 303 is a buffer spring 307 which has two functions, first, to hold the stud screw 305 against the right hand portion of the slot 304 and sec-

ond, to give the pickup beam as a whole a 65 tendency to turn in a clockwise direction (Fig. 2) about the stud screw 305, this latter tendency being given on account of the hole 308 into which the spring 307 is fastened to the bracket 303, being above a line drawn 70 from the stud 306 to the stud screw 305. If it is desired, the stud screw 305 may be given an eccentric bearing in the pickup beam 302, and thus the tendency of the pickup beam to rotate about the stud screw 305 may be 75 adjusted. In the forward part of the pickup beam 302 is riveted a second stud 309, which has a flange 310, serving as a guide for the pickup guard 311 to be hereinafter described, and a stud portion 312, which reciprocates 80 in the slot 313 in the plate 314 mounted on the frame work 29. The slot 313 is provided at its left hand end (Fig. 22) with a cam surface 315 which serves to depress the pickup beam 302 and therefore disconnect the hook 85 301 from its then connecting totalizer heel 300, when the stud 312 engages the surface 315.

On the plate 314 is mounted an adjustable plate 316, having therein a recess 317, which 90 is adjusted to be under the stud 312 when the cross totalizer is retracted to its normal position by the spring 275.

The plate 316 has a surface 318 which forms a continuation of the lower part 319 95 of the slot 313. One of the main objects for the adjustment of the plate 316 is to positively constrain the stud 312 and by it the pickup beam 302 so that the hook 301 cannot become accidentally disconnected 100 from its then connected vertical totalizer heel 300. As will be seen from Fig. 22, the only place that the pickup beam 302 has any freedom of vertical motion is when the stud 312 is opposite the recess 317. Freedom at 105 this point is necessary to permit the return of the truck 130 on which are mounted the vertical totalizers, while the cross truck 256 is in its normal position. It is obvious that during such return the heels 300 on the several vertical totalizers will snap idly over the hook 301.

The plate 314 has pivoted on it at 320 an auxiliary dog 321, which is held in contact with the lower side of the pickup beam 302 by a spring 322 fastened to a stud 323, in the frame work 29. The dog 321 has turned up from it an ear 324 which contacts with the lower side of the plate 314, and thus holds the dog in a normal position. 115 The bottom side of the pickup beam is so shaped that when the pickup beam is in the position shown in Fig. 22, the ear 324 is not in contact with the plate 314, but when the pickup beam is in a position to be disconnected from the heel of the vertical totalizer, that is, when the stud 312 encounters the cam 315, the ear 324 is not thrown into 120 125

contact with the pickup beam and only the force of the spring 307 is required to be overcome when the pickup beam is disconnected from the heel of the vertical totalizer.

The adjustable plate 316 has on it a series of numbers denoting the adjustments corresponding to different widths of the cross totalizers. Two screws 325 and 326 10 serve to hold the plate 316 to the plate 314, a series of tapped holes being provided in the latter.

Rotatably mounted on the stud screw 305 is the pickup guard 311, it being held in its 15 position by a washer 327. The function of this pickup guard is to prevent overthrow or rebound of the cross truck when the same is picked up by the vertical truck. The pickup guard is perhaps best shown in Figs. 20 22 and 26, reference to which will disclose that the guard is provided with a nose 328 adapted to rise to the right of the totalizer heel 300 and constrain the same between the hook 301 and this nose 328. The lower side 25 of the pickup guard 311 is provided with a cam 329 and a slot 330, which is adapted to engage a pin 331 mounted in the adjustable plate 316. There is also a hole 332 around the stud 309 and which is adapted to be acted 30 on by said stud. When the stud 312 encounters the cam surface 315 and thereby 35 disengages the pickup beam from the heel 300, the pickup guard 311 is simultaneously depressed. When the cross truck has been 40 retracted by the spring 275 to its normal position, the cam surface 329 engages the pin 331 which enters the slot 330 and depresses the pickup guard 311 to a position where it will not engage any of the vertical totalizer heels 300.

The pickup guard 311 has at its rear end 45 an ear 333 on which is a pin 334. A compression spring 335 surrounding the pin 334 and bearing against the bracket 303, serves to give the pickup guard 311 a tendency to rotate in the same direction as the pickup beam 302.

From the above it is apparent that when 50 the cross truck is in its normal position, the pickup guard 311 will be out of the way of any of the totalizer heels 300, and therefore the vertical truck may be moved backward without interference. However, as soon as 55 the cross truck is displaced from its normal position, the slot 330 will be withdrawn from the pin 331 and the pickup guard 311 will rise and therefore the cross truck will be positively constrained by the totalizer heel 300, since the hook 301 will prevent motion of the 60 cross truck in one direction, and the nose 328 will prevent motion of the cross truck in a contrary direction.

This guard is of great importance since 65 it prevents the cross truck from getting out of its decimal relation to the vertical truck.

When the vertical truck is advanced by means of the tabulator keys, the hook 301 will receive a sharp blow from the heel 300. While the force of this blow will be minimized by the buffer spring 307 which permits the momentary relative yielding between the two trucks, yet the force of the blow may cause the pickup beam 302 and its connected cross truck to bounce or move faster than the vertical truck. The gear shifts.

In performing the operations for which my machine is adapted, it is necessary to change the operative connections of either one or both of the master wheels with the numeral keys. It may be desired to enter 95 numbers either in addition or subtraction or not at all, into the vertical actuator. I shall hereinafter refer to the position of the gear shift in which the keys do not affect the totalizer as the disconnect position. Similarly it may be necessary to enter numbers into the cross actuator in either addition or subtraction, or it may be necessary to disconnect the cross actuator from the operation of the numeral keys. As previously 110 explained in connection with the description of the vertical and cross actuators, the operative relation of the master wheel to the numeral keys is controlled by the position of the gear shift rod 113 for the upper actuator and the position of the gear shift rod 176 for the lower actuator. Each of these rods may have three positions, thereby determining three possible conditions. When these rods are in their extreme left hand positions, both master wheels will produce addition in their respective totalizers upon the operation of any of the numeral keys. When either rod is in its extreme right hand position, operation of the numeral keys will produce subtraction, and when the rods are in their middle or disconnect position, actuation of the numeral keys will not result in any rotation of the associated master wheel, and therefore no number will be entered in the then associated totalizers. It is desirable that these gear shift rods be capable of independent movement, that is, any one of three conditions of the vertical actuator may exist simultaneously with any one 120 125 130 135 140 145 150 155 160 165 170 175 180 185 190 195 200 205 210 215 220 225 230 235 240 245 250 255 260 265 270 275 280 285 290 295 300 305 310 315 320

of the three conditions of the cross actuator. Obviously this will give rise to 9 possible combinations of the two actuators.

It is also desirable that the cross actuator have two controls, that is, that it be automatically controlled by motion of the vertical truck, thereby enabling the machine to be set up to perform a predetermined program of cross calculation. It is also desirable that the cross actuator have an independent manual control for the reason that even if the machine is set up for a definite program, it may be desirable to temporarily cancel this program and calculate according to a program determined by a manual control for the cross actuator. This manual control of the cross actuator will therefore give rise to three additional conditions, viz.:—manual addition, manual disconnect or manual subtraction, making 18 possible combinations.

If one could depend on the operator's never making a mistake, the above enumerated combinations would be sufficient for all purposes. However, occasionally the operator will enter a wrong number into the machine. The easiest way to correct this insertion is to throw the machine into the reverse of its condition when the erroneous number was inserted, and enter the erroneous number a second time, thereby canceling the first insertion. The correct number is then entered. This consideration makes it desirable to have a common reversing lever which, when operated, will put the machine into the reverse of its normal condition. Obviously the machine could be thus reversed by independently reversing both the upper and cross actuator, but it is to be remembered that while the vertical actuator is always under manual control, the cross actuator may be either under manual control or automatic control and in either of these controls may occupy any one of three possible positions, that is, it may be in addition, subtraction, or disconnect. Therefore correct reversing of the two actuators becomes an extremely complicated problem and it is highly desirable in order to avoid errors on the part of the operator, that there be a single lever which, when operated, will reverse both actuators regardless of their condition. Since the machine may be in any one of the 18 combinations above referred to when a reversal is desired, it is obvious that the presence of this universal lever doubles the number of possible combinations, making some 36 possible combinations of the two actuators. While some of these combinations are of course duplicates, yet it will be appreciated that the problem of providing a universal reversing lever is a somewhat complicated one.

In Fig. 17 I have shown a perspective view of the gear shifts. There is, first, a

handle 336 which controls the vertical actuator. There is a similar handle 337 which manually controls the cross actuator. Each of these handles has three possible positions, viz., addition, disconnect, or subtraction. There is an automatic shift handle 338 whose function is to change the cross actuator from automatic to manual control and vice versa. In addition there is a universal correcting handle 339, whose function is to simultaneously reverse the condition of both actuators when it is desired to make a correction. It is to be noted that I consider a disconnect position the reverse of a disconnect position since if an actuator is in a disconnect position there will be no number inserted into its associated totalizer, and therefore in case a correction is made, this correction should be limited to but one totalizer.

Reference to Fig. 1 will disclose that the handle 336 is provided with an escutcheon plate 340 having therein three locating positions 341, 342, and 343, marked respectively "A," for add, "D" for disconnect, and "S" for subtract. The handle 336 is provided with a spring 289 which bears against the frame work 29 of the machine and serves to maintain the handle in its located positions.

The manual control for the cross actuator which I shall hereinafter term the "cross control" is also provided with an escutcheon plate 344 which is similarly marked with the three letters "A," "D" and "S," denoting addition, disconnect and subtraction. The lever 337 is rigid to a shaft 345, rotatably mounted in the frame work and is provided with three notches 346, co-operating in which is a locating cam 347 on a lever 348, pivotally mounted in the frame work at 349. A spring 350 between said lever and the stud 351 in the frame work serves to maintain the contact between the cam 347 and the notches 346, thereby maintaining the lever 337 (Fig. 6) in any of the three possible positions to which it may have been moved. The automatic lever 352 (Figs. 1 and 7), serves to shift the cross actuator from automatic to manual control by means hereinafter to be described. This lever is mounted rotatably on the frame work on the stud 353 and has riveted in it a pin 354 which contacts with one or the other of two notches 355 in the lever 356 rotatably mounted in the frame work at 357. A spring 358 extends from the lever 356 to the stud 323 in the frame work. Thus the lever 352 is maintained in either of its two possible positions.

The universal correcting lever 339 is perhaps best shown in Fig. 8. This lever is rotatably mounted on a stud 448 in the frame work and its left end has a link 449 pivoted therein. The other end of this link is pivoted to one arm 359 of a bell crank 360 rotatably mounted on the stud 361 in the frame work. A spring 362 (Fig. 8) ex-

130

tending from the arm 359 to a stud 363 in the frame work serves to maintain the universal correcting lever in the position shown in Fig. 8. A latch 364 pivoted to a stud in the frame work at 365 serves to maintain the universal correcting lever in a depressed position by engagement of the nose 366 with the portion 367 of the universal correcting lever 339.

10 The universal correcting lever 339 has extending from it a link 368 to an arm 369 rotatably mounted on the ribbon shift button 370 of the typewriter. As is well-known in the Remington typewriter, this ribbon shift may be pulled in or out, thereby establishing or dis-establishing a connection between a notch 371 rigid on said rod and a pin 372 riveted in the arm 369. Thus when the universal correcting lever is operated, 20 the typewriter ribbon is shifted to print in red. However, if it is so desired, the operator may disable this connection by pulling the knob 370 so that the pin 372 does not engage the notch 371.

25 Having now described the different handles which are used for manipulating these various gear shifts, I will enter upon a description of the gear shifts themselves. Describing first the shift of the vertical actuator, reference to Fig. 17 will disclose that the gear shift rod 113 is pivotally connected to a crank 373 on a shaft 374 rotatably mounted in the frame work 29 of the machine. On the other end of this shaft is 35 a crank 375 in which is a pin 376, the position of which is controlled by a V-shaped slot in the floating lever 377, (Figs. 5 and 17). The lever 377 may be controlled from either of two points, first, the stud 378 40 whose position is controlled by the universal correcting lever in a manner herein-after to be described, second, from the stud 379, whose position is controlled by the vertical control lever 336.

45 Describing the first control, referring particularly to Fig. 19, it will be seen that the arm 380 of the bell crank 360 has in it a slot 381, and a pin 382 is riveted in a flat spring 383 mounted on the bell crank 360. On the pin 382 are mounted, on either side of the bell crank 360, the flat links 384 and 385, in which is riveted the stud 378 before referred to. This stud is guided horizontally by the slot 386 (Fig. 5) in a 55 T-shaped plate 387 mounted in the frame work. The floating lever 377 has in it a slot 388 (Fig. 5) through which passes the stud 378. Thus motion of the universal correcting lever 339 will move the center of 60 the floating lever 377.

The function of the spring 383 is to compensate for any inaccuracies in the motion of the universal correcting lever 339. The motion of the stud 378 is determined by the 65 extent of the slot 386. When said pin is in

one position, it is held firmly against said slot by the spring 382. When the universal correcting lever is thrown to its other position, the stud 378 contacts with the other end of the slot 386, the flat spring 383 yielding sufficiently to compensate for any excess motion of the universal correcting lever 339.

Reference to Fig. 17 will render apparent the connections between the vertical control and the top part of the stud 379. This stud has a large head 389 and a cylindrical portion traveling in the slot 390 in the T-shaped piece 387. Then there is a smaller portion which turns freely in a hole in the floating lever 377, and the end of the stud is riveted 70 to a link 391 which is pivoted on an arm 392 of the bell crank 393 rotatably mounted on the stud 361 and having an arm 394 connected by a link 395 to the vertical control lever 336. Referring to the position of the 80 parts as shown in Fig. 5, and regarding the stud 378 as stationary, it is obvious that motion of the vertical control lever 336 will cause the pin 376 to rise to the top of the V-shaped slot in the floating lever 377. This 85 motion will change the gear shift rod 113 from its extreme right hand position, corresponding to subtraction, to its extreme left hand position, corresponding to addition. The intermediate stud will of course correspond to the disconnect position as before 90 explained. Now if, instead of moving the stud 379, one were to move the stud 378 by means of the universal correcting lever, it is obvious that exactly the same action 95 would occur, that is, the gear shift rod 113 would be thrown from the position shown in Fig. 17 into its addition position. If the pin 376 were at the apex of the V-shaped slot in the floating lever 377 and one were 100 to move the universal correcting lever, thereby moving the stud 378, the pin 376 would then be in the extreme right hand portion of the V-shaped slot, Fig. 5, thus 105 throwing the machine to the reverse. When 110 the vertical actuator is in the disconnect position, the pin 376 stands about half way up the V-shaped slot in the floating lever 377, and motion of the stud 378 will throw the floating lever so that the pin 376 will 115 stand half way up the other side of the V-shaped slot.

To recapitulate the action of the vertical control, the position of the gear shift rod 113 is determined by the position of the 120 floating lever 377. The position of this lever is determined by the position of two points, viz., the stud 378 and the stud 379, one of these pins being under control of the universal correcting lever and occupying either 125 one of two positions, that is, the position shown in Fig. 5, or the position in which the stud 378 is against the other end of the slot 388. The position of the floating lever 377 is also determined by the position of the 130

stud 379, whose position in turn is determined by the position of the vertical control lever 336. In respect to the V-shaped slot, the pin 376 may have any one of five possible positions. Two of these positions are the ends of the V corresponding to a position of the rod 113 which determines subtraction. The third position is when the pin 376 is at the vertex of the V, thereby determining addition, and the two additional positions are when the pin is halfway up the other side of the V, thereby determining the disconnect position. Corresponding to any position of the stud 379, the motion of the stud 378 due to the actuation of the universal correcting lever 339 will reverse the position of the gear shift rod 113 and thereby reverse the relation of the vertical master wheel 106 to any of the numeral keys.

I shall now describe the action of the gear shift for the cross totalizer. Similar to the vertical totalizer, the position of the gear shift rod 176 is controlled by the position of the pin 396 mounted in a crank 397 on the end of the rod 398, rotatably mounted in the frame work. On the other end of the rod 398 is a crank 399 from which extends the link 400 to the lever 401 turning on the pivot 402 in the slotted post 403 in the frame work. At the other end of the lever 401, the gear shift rod 176 is pivoted at 404. Therefore motion of the pin 396 will result in motion of the gear shift rod 176.

The position of the pin 396 is controlled by the position of the second floating lever 405, whose position is determined by the position of the two pins 406 and 407, just as the position of the floating lever 377 is determined by the position of the two studs 378 and 379. The pin 406 is controlled by the links 384 and 385 which are riveted together by the stud 408 to hold them in proper alignment. The pin 406 has a bearing in a T-shaped piece 409, which is similar to the T-shaped piece 387. Since the action of the floating lever 405 is precisely the same as the analogous lever 377, it will not be necessary to further describe the same.

However, in the motion of the pin 407, another problem arises, since this pin, as before noted, must be under either automatic control or manual control and the device must be provided for shifting from one control to the other. The automatic control of the pin 407 is provided by the two links 410 and 411 which are pivotally mounted on the levers 412 and 413 on the shaft 414 rotatably mounted in the frame work. A crank 415 is mounted on the end of this shaft, and on a stud 416 in this crank is mounted the roller 417 which is adapted to contact with and be moved by the cams 418, 419 and 420 on the vertical totalizers 179, 180 and 182.

The links 410 and 411 are provided with

V-shaped slots 421 and 422 having a recess in the bottom thereof adapted to grasp and move the pin 407. This pin is riveted in the floating lever 405 and has a portion 423 which moves in the slot 424 in the T-shaped piece 409. The ends of the pin are grasped by the two pieces 410 and 411, and are controlled by these pieces when the pin is in engagement with the recess at the bottom of the slots 421 and 422.

70

75

The manual control of the cross actuator is effected, as before noted, by the handle 337, which is mounted on the shaft 345 turning in the frame work. On the end of this shaft is the crank arm 425 on which is pivoted the link 426 extending to a lever 427 pivoted on the frame work at 428. On the upper end of this lever is mounted a link 429 having therein a triangular opening 430 at the top of which is the recess 431 adapted to engage the pin 407. Obviously, if the links 410 and 411 were dropped from engagement with the pin 407 and the recess 431 were engaged therewith, the position of this pin would then be controlled not by the automatic control roller 417, but by the position of the cross control lever 337. In order to provide for this shifting, I have joined the end of the automatic shift lever 338 by the link 432 to a lever 433 pivoted on the frame work at 428. Riveted in this lever is a pin 434 which engages a slot 435 in a lever 436, pivoted in the frame work at 437, and having therein a pin 438 which engages a slot 439 in the link 410, and a slot 440 in the link 429. Rotation of the lever 433 about its axis 437 will result in disengaging the recess in the bottom of the slots 421 and 422 from the pin 407 and the engagement of the recess 431 with said pin 407. It is to be observed that the links 410 and 411 are connected by a pillar 441 so that motion of the link 410 will also result in motion of the link 411. When the cross actuator is thus under manual control, it is desirable to throw the roller 417 out of the path of the cams 418, 419 and 420 so as to avoid useless motion of the roller 417 and its associated parts. To this end, I have provided the pin 442 in the lever 433 and this pin engages with an extension 444 on the lever 412. When the cross actuator is thrown from automatic to manual control, motion of the pin 442 will therefore raise the extension 444 and consequently depress the roller 417 out of the way of the cams on the vertical totalizers. The spring 445 extending from an arm 446 in the lever 412 to a stud 447 in the frame work serves to maintain the roller 417 and its associated parts in a position to be depressed by the cams on the vertical totalizers when the cross actuator is in automatic control.

85

90

95

It is not necessary to go into a detailed analysis of how the position of the pins 406 and 407 will be controlled when the cross actuator is in manual control. The action of the cross actuator is controlled by the handle 337, which is mounted on the shaft 345 turning in the frame work. On the end of this shaft is the crank arm 425 on which is pivoted the link 426 extending to a lever 427 pivoted on the frame work at 428. On the upper end of this lever is mounted a link 429 having therein a triangular opening 430 at the top of which is the recess 431 adapted to engage the pin 407. Obviously, if the links 410 and 411 were dropped from engagement with the pin 407 and the recess 431 were engaged therewith, the position of this pin would then be controlled not by the automatic control roller 417, but by the position of the cross control lever 337. In order to provide for this shifting, I have joined the end of the automatic shift lever 338 by the link 432 to a lever 433 pivoted on the frame work at 428. Riveted in this lever is a pin 434 which engages a slot 435 in a lever 436, pivoted in the frame work at 437, and having therein a pin 438 which engages a slot 439 in the link 410, and a slot 440 in the link 429. Rotation of the lever 433 about its axis 437 will result in disengaging the recess in the bottom of the slots 421 and 422 from the pin 407 and the engagement of the recess 431 with said pin 407. It is to be observed that the links 410 and 411 are connected by a pillar 441 so that motion of the link 410 will also result in motion of the link 411. When the cross actuator is thus under manual control, it is desirable to throw the roller 417 out of the path of the cams 418, 419 and 420 so as to avoid useless motion of the roller 417 and its associated parts. To this end, I have provided the pin 442 in the lever 433 and this pin engages with an extension 444 on the lever 412. When the cross actuator is thrown from automatic to manual control, motion of the pin 442 will therefore raise the extension 444 and consequently depress the roller 417 out of the way of the cams on the vertical totalizers. The spring 445 extending from an arm 446 in the lever 412 to a stud 447 in the frame work serves to maintain the roller 417 and its associated parts in a position to be depressed by the cams on the vertical totalizers when the cross actuator is in automatic control.

110

115

120

125

130

It is not necessary to go into a detailed analysis of how the position of the pins 406 and 407 will be controlled when the cross actuator is in manual control.

and 407 determines the position of the cross gear shift rod 176, since this action is in every respect analogous to the gear shift rod 113 of the vertical actuator. The chief difference in the action of the floating lever 405 from that of the floating lever 377 is in the fact that the former lever may be controlled either automatically or manually. However, I have described provisions for 10 effecting either of these controls and for changing from one to the other. Obviously the motion of the universal correcting lever as transmitted by the links 384 and 385 to the pin 406 will reverse the cross actuator 15 just as effectually as such motion will reverse the vertical actuator. The motion is therefore universal. I am able to obtain any 20 of the entire number of theoretical combinations of the two actuators. The vertical actuator may be manually controlled for addition, subtraction or disconnect. The cross actuator may be manually controlled for these three conditions and also automatically controlled for these three conditions and in 25 any of the various combinations which may arise from these controls, the operation of the universal correcting lever 339 will throw each actuator into the reverse of its former condition.

30   *The cross totalizer interlock.*

The function of this interlock is to prevent the operation of the cross totalizer in case the same should be accidentally disconnected from a vertical totalizer and further to prevent the actuation of the cross totalizer in case the machine should be operated as follows:

Assume that the operator has entered a 40 number into both totalizers and that the truck 130 has carried the vertical totalizer to the first space to the right of the master wheel at which space, as before noted, the hook 301 will have become dis-engaged from the heel 300 and the spring 275 will have returned the cross totalizer into its normal position. Assume that the operator then discovers that she has entered the wrong 45 number and wishes to make a correction, and for this purpose she returns the vertical truck to the decimal place in which the correction is to be made. Obviously the vertical truck will not be returned far enough to pick up the hook 301 and therefore the 50 cross totalizer will not be in the proper decimal relation with the vertical totalizer. If the operator were now to actuate the numeral keys of the machine, a number would be entered into the vertical totalizer, but 55 owing to the fact of the cross totalizer remaining in its normal position, would not be entered in this latter totalizer. Obviously an error would result.

The function of my interlock is also to

prevent an operation of the above described 65 nature. In a general way, the operation of my improved interlock may be described as preventing the operation of the numeral keys of the machine when the cross totalizer is not in its proper decimal position and a 70 vertical totalizer is in a calculating zone. It will be perhaps best understood by referring to the perspective view shown in Fig. 21, reference to which will disclose that the 75 finger 460 is rigidly mounted on the rock-shaft 77 and enters a slot 461 in a stud 462 rigidly mounted in the frame work 29. Since the rock shaft 77 is operated every time a numeral key is actuated, it is evident that if by any means one were to prevent 80 the entry of the finger 460 into the slot 461, the numeral keys of the machine would be locked. To this end, there is provided a pendant 463 which is pivoted at 464 on a lever 465 pivoted at 466 in the frame work 85 29. The lower end of the lever 465 is engaged by a slot 467 in a piece 468, which is slidably mounted in the frame work 29, and has a hole 469 through which passes the lever 283, which as before noted, is pivoted on the frame work at 284. A flat spring 470 is fastened to the lever 283 and by bearing against the plate 262 serves to 90 give the lever 283 a tendency to move in a counter-clockwise direction, Fig. 21. 95

In the pendant 463 is a slot 471 in which works the end of the stud 472, which is riveted to a link 473 and has a portion 474 which slides in and is guided by a slot 475 in the plate 314. The other end of the link 100 473 is pivoted on a crank arm 476 of the U-shaped piece 477, which is rotatably mounted on the shaft 414. Extending beyond the shaft 414 is an arm 478 on which is mounted a roller 479, which is adapted to 105 contact with and be depressed by a cam 480 mounted on all of the vertical totalizers. A flat spring 481 fastened to the frame work and bearing against the arm 478 serves to 110 give this arm a tendency to rotate in a clockwise direction and thereby rise into the path of the totalizer cams 480. The pendant 463 has a nose 482 which is adapted to enter between the finger 460 mounted on the rock shaft 77 and the slot 461. Obviously when 115 the nose 482 is between said finger 460 and the slot 461, motion of the rock shaft and consequently motion of the numeral keys will be prevented. It is obvious that inasmuch as the lever 283 is held against the 120 plate 262 by the adjustable plate 282 on the cross truck 256, and that as soon as said cross truck is picked up by a vertical totalizer, the spring 470 will cause the lever 283 to follow the plate 282 for a short distance 125 that this rotation of the lever 465 on its pivot 466 will lift the nose 482 from the path of the finger 460. It follows that

whenever the cross truck is displaced from its normal position the locking action of the nose 482 will be ineffectual.

Whenever the roller 479 is not depressed by a cam 480, the nose 482 will be in the position shown in Fig. 21, that is, the nose 482 will be out of the path of the finger 460. Therefore this determines that whenever the vertical totalizer is not in a calculating zone, the nose 482 will not be in a position to lock the machine. However, if the vertical totalizer is in a calculating zone, the cam 480 will engage and depress the roller 479. This will rock the pendant 463 on its bearings 464 and in case the cross totalizer should then be in its normal position, the nose 482 will be rotated so as to close the opening of the slot 461 and the operation of the machine will be prevented.

It may be asked why it is necessary to make the action of this lock dependent upon the fact of the vertical totalizer's being in the calculating zone and why it would not be sufficient to have the action of the lock determined by the position of the cross totalizer alone. The answer to this is that if the machine were so constructed, it would prevent the writing of figures such as dates and numbers which were not required to be added. The lock is therefore made dependent upon two independent factors. First, the position of the cross totalizer, and second, the position of the vertical totalizer, and the lock, as before noted, is so constructed as to be effective only when the cross totalizer is in its normal position and a vertical totalizer is in the adding zone.

The link 473 has on it a mark 483 which serves as a guide for the adjustment of the plate 316. This plate, it will be remembered, is adjusted concurrently with the plate 282 to provide for the use of different widths of cross totalizers on the cross truck 256.

The cross gear shift rod 176 may be controlled by a number of handles, since its position may be determined by the position of the roller 417, the cross control handle 337, the automatic shift 338, or the universal correcting lever 339. Obviously if any of these handles or the roller 417 are not in their proper positions, the cross gear shift rod will be out of position and an error may result. To guard against this possibility, I have provided three notches 484, 485 and 486 in said rod, Fig. 20, and have rotatably mounted a plate 487 on the post 173 of the cross actuator, a collar 488 serving to hold the plate 487 in its properly alined position. This plate has in it a hole 489 to avoid interference with the cross shifter 170, and also a slot 490 working in which is a pin 491 mounted on an arm 492, rigid with the cross rock shaft 160. In the rear portion of this plate is an aliner cam 492 which is provided

with a beveled end 494 adapted to enter and align any one of the slots 484, 485 or 486. The plate 487 is of course rocked on the post 173 by the pin 491 each time the rock shaft 160 is actuated or each time a numeral key 32 of the machine is operated. In case the cross gear shift rod 176 is not in its proper position due to accidental displacement of some of the handles which control the position of said rod, the beveled portion 494 of the cam 493 will either not be able to enter any of the notches 484, 485 or 486 in which case the keys of the calculating machine will be locked, or it will enter said slots and align the gear shift rod 176 to its proper position.

I wish to call attention to the extreme simplicity of this locking device, since by the simple expedient of providing the cross gear shift 176 with three slots and providing a cam to enter one of said slots whenever a numeral key is operated, I am able to guard against the accidental displacement of any of the four possible means of control of the cross gear shift rod 176.

The many uses of my improved cross foot-ing machine will be apparent to those skilled in the art. It is possible to set up any desired program in calculation for the cross totalizer by means of changing the cams 418, 419 and 420 mounted upon the vertical totalizers. These cams are made in two different heights. The absence of a cam as shown on totalizer 181 determines that the cross totalizer shall operate in addition, since the absence of the cam permits the spring 445 to raise the roller 417 to its highest level. When the cam 418 shown on the vertical totalizer 179 engages the roller 417, it will de-press the same to its lowest level and this will determine that the cross totalizer shall operate in subtraction. The cam 419 being of intermediate height will hold the roller 417 in the middle position, which will determine that the cross gear shift rod 176 will be in a position which determines that the number set up on the numeral keys shall not go into the cross totalizer at all. Obviously, as many vertical totalizers may be put on the truck 130 as is desired, and these totalizers may be any capacity and be made to calculate in any desired table.

It is not necessary for me to give any specific examples of work which may be ad-vantageously done on my machine. I may mention the particular problem known as the bank statement problem. This is a statement which is rendered to the customers of the bank at the end of the month and shows, first, the total number of the cus-tomer's checks which have been honored by the bank, the customer's deposits, the cus-tomer's balance, and the customer's balance day by day. The calculation of these state-ments may be done by the cross footing

totalizer and the vertical totalizers used to accumulate the grand totals of the entire amounts written by the operator. These 5 grand totals may of course be checked against totals obtained by the handling of the same items by other parts of the accounting force of the bank.

Many advantages result from the use of my improved structure herein described. I 10 consider the novel connecting means between the vertical and cross trucks, especially when taken in connection with the pawl 452, of great utility. Due to the desirability of operating this machine rapidly, 15 the typewriter carriage is usually advanced by a tabulating operation. In the usual construction, the typewriter carriage is liable to rebound when arrested by the tabulator stop, and since the cross truck is then 20 connected with the typewriter carriage through the medium of the heel 300 on a vertical totalizer, the cross truck must rebound at least as much as the typewriter carriage and is free to rebound even more. 25 My improved construction herein disclosed prevents rebound of the typewriter carriage and also, by the use of the pickup guard 311, the rebound of the cross truck. Therefore it is impossible for an operator 30 to insert a number in a vertical totalizer without at the same time inserting it in the proper decimal place of the cross totalizer.

I consider the tension put upon the pickup beam 302 by the auxiliary dog 321 and 35 its associated spring 322 of great importance, especially in view of the peculiar arrangement by which this tension is taken off of the pickup beam when said beam arrives at the point where it is disconnected 40 from the vertical totalizer. Obviously the work of disconnecting the pickup beam from the vertical totalizer is thrown on the typewriter carriage spring and it is desirable that this work shall be as small as possible, 45 since the typewriter carriage is very heavy and the spring has already a great deal of work to do. On the other hand, it is desirable that the tendency of the hook 301 to engage with a heel 300 should be as strong 50 as possible, since the stronger the force tending to engage the hook 301 to a heel, the less will be the probability of said hook failing to hold in case the hook is in the position shown in Fig. 22, that is, the 55 stud portion 312 is free to move into the recess 317 and a heel 300 is brought violently into contact with said hook 301. The action of my improved dog herein described gives the pickup beam 302 an extra tension 60 to engage the totalizer heels when the cross truck is in its normal position, and by reason of the bottom of said pickup beam being so shaped as to be out of engagement with the dog 321 when the pickup beam

has reached its disconnecting position, the 65 resistance of the typewriter carriage is no more than usual. This feature of giving a varying tension to the pickup beam 302 is of great advantage and I wish to claim the same broadly.

It will be recognized that the machine herein described contains inventions disclosed and claimed in certain pending applications of myself and Arthur F. Poole, and I do not wish to claim herein any of said 75 inventions.

Many changes and alterations could be made from the precise structure herein disclosed without departing from the spirit of my invention since I claim:

1. In a calculating machine, the combination of a main carriage, a decimal carriage, means to intermittently connect said decimal carriage to said main carriage whereby said decimal carriage makes a plurality of reciprocations during one traverse of said main carriage, a set of numeral keys, a lock to prevent the operation of said keys, said lock being arranged to be effective when said decimal carriage occupies a normal position, and means to disable said lock when said main carriage is in a predetermined position.

2. In a calculating machine, the combination of a main carriage, a decimal carriage, 95 means to connect said decimal carriage to said main carriage intermittently during a single traverse of said main carriage, and a lock to prevent the operation of the machine, said lock being jointly controlled by 100 said carriages.

3. In a calculating machine, the combination of a decimal carriage, a second decimal carriage, and a lock for the machine controlled by the joint action of said decimal 105 carriages.

4. In a calculating machine, the combination of a main carriage, a decimal carriage, means to connect said decimal carriage intermittently to said main carriage whereby 110 said decimal carriage makes a plurality of reciprocations during one traverse of said main carriage, a set of numeral keys, a lock to prevent the operation of said keys, said lock being controlled by said decimal carriage, and means mounted on said main carriage and adapted to render said lock effective when said carriage is in a predetermined position.

5. In a calculating machine, the combination of a main carriage, a decimal carriage, means to connect said decimal carriage intermittently to said main carriage whereby 115 said decimal carriage makes a plurality of reciprocations during one traverse of said main carriage, a set of numeral keys, a lock to prevent the operation of said keys, said lock being controlled by said decimal car-

riage, and a series of cams mounted on said main carriage and adapted to render said lock effectual.

6. In a calculating machine, the combination of a main carriage, a decimal carriage, means to connect said decimal carriage intermittently to said main carriage whereby said decimal carriage makes a plurality of reciprocations during one traverse of said main carriage, a set of numeral keys, a lock to prevent the operation of said keys, said lock being controlled by said decimal carriage, and a series of adjustable cams mounted on said main carriage and adapted to render said lock effectual.

7. In a calculating machine, the combination of a main carriage, a decimal carriage, means to connect said decimal carriage intermittently to said main carriage, whereby decimal carriage makes a plurality of reciprocations during one traverse of said main carriage, a set of numeral keys, a lock to prevent the operation of said keys, said lock being controlled by said decimal carriage, and a series of independently adjustable cams mounted on said main carriage and adapted to render said lock effectual.

8. In a calculating machine, the combination of a set of numeral keys, means to prevent the operation of said numeral keys including a floating lever controlled from two points, the effectiveness of said lock depending upon the position of said floating lever.

9. In a calculating machine, the combination of a lock for preventing the operation of said machine and a floating lever controlling the effectiveness of said lock.

10. In a calculating machine, the combination of a set of numeral keys, and means to prevent the actuation of said numeral keys, said means including a floating lever, one point of which is controlled from one portion of the calculating machine, and another point of said lever being controlled by the position of a second portion of said calculating machine.

11. In a calculating machine, the combination of a set of numeral keys, and means to prevent the operation of said numeral keys, said means including a floating lever controlled from two points, the position of one of these points being automatically controlled by one portion of said calculating machine and the position of the other of said points being controlled by another portion of said calculating machine.

12. In a calculating machine, the combination of a jumping decimal carriage, a second decimal carriage, a floating lever, means to control the position of one part of said lever from the position of said jumping carriage, and means to control

another part of said lever from said second decimal carriage.

13. In a calculating machine, the combination of a jumping decimal carriage, a second decimal carriage, a floating lever, means to control one part of said lever from the position of said jumping carriage, means to control another part of said lever from said second carriage, and a lock for the machine controlled by said floating lever.

14. In a calculating machine, the combination of a set of numeral keys, a universal member adapted to be moved by any of said keys, a lock for said universal member, a decimal carriage, a second decimal carriage, and means controlled by the position of said decimal carriage to determine the effectiveness of said lock.

15. In a calculating machine, the combination of a set of numeral keys, a universal member adapted to be moved by any of said keys, a lock for said universal member, a decimal carriage, a second decimal carriage and a floating lever controlled jointly by the position of said decimal carriages to determine the effectiveness of said lock.

16. In a calculating machine, the combination of a moving carriage having a series of vertical totalizers mounted thereon, a cross totalizer adapted to be intermittently connected to said moving carriage, a set of numeral keys, a universal member moved by said numeral keys, a lock for said universal member, and means controlled jointly by the position of said vertical and cross totalizers to determine the effectiveness of said lock.

17. In a calculating machine, the combination of a moving carriage having a set of vertical totalizers mounted thereon, said totalizers being independently adjustable on said carriage, cams mounted on said totalizers, a cross totalizer adapted to be intermittently connected to said carriage, a set of numeral keys, and a lock for said numeral keys controlled jointly by the position of said cross totalizer and said cams.

18. In a calculating machine, the combination of a moving carriage, a cross decimal carriage adapted to be intermittently connected to said moving carriage, a spring to maintain said cross carriage in a normal position, a set of numeral keys, a lock for said numeral keys controlled by said cross carriage when the same is in its normal position, and an adjustable stop mounted on said cross carriage to thereby determine its normal position.

19. In a calculating machine, the combination of a moving carriage, a set of lugs moving with said carriage, a cross decimal carriage adapted to be intermittently connected to said lugs and thereby move synchronously with said moving carriage, a

- spring tending to return said cross carriage to a normal position and an adjustable stop coöperating with said cross carriage to determine its normal position.
- 5 20. In a calculating machine, the combination of a set of numeral keys, a lock for said numeral keys, a floating lever determining the effectiveness of said lock, a main carriage, an adjustable cam on said main carriage, a roller coöperating with said cam, said cam and roller connection serving to determine the position of a point in said floating lever, a cross decimal carriage, and means connecting said decimal carriage to a second point in said floating lever whereby the position of the same and the effectiveness of said lock is determined by the joint action of the two said carriages. 70
- 10 21. In a calculating machine, the combination of a main carriage, a plurality of vertical totalizers having a series of connecting locations mounted thereon, a cross decimal carriage, means to intermittently connect and disconnect said cross decimal carriage with said connecting locations, a set of numeral keys, a lock for said numeral keys controlled jointly by the position of said decimal carriages, a part of the control for said lock being simultaneously adjustable with a connecting location, whereby an adjustment of the point of connection of said cross totalizer also simultaneously adjusts the point of operation of said lock. 75
- 15 22. In a calculating machine, the combination of a main computing carriage, a cross computing carriage, a series of connecting locations on said main carriage, a hook mounted on said cross carriage, and adapted to engage said locations, thereby intermittently establishing a connection of the two said carriages, a spring urging said hook into the path of said connecting locations, and means to give said hook a greater tension to engage said connecting location 80 when said cross carriage is in its position of connecting than when in its position of disconnecting. 85
- 20 23. In a calculating machine, the combination of a cross decimal carriage, a hook mounted on said carriage, a spring tending to turn said hook in one direction, and an auxiliary tension device to vary the effective force of said spring during the travel of said cross carriage. 90
- 25 24. In a calculating machine, the combination of a cross decimal carriage, a hook mounted thereon, means tending to turn said hook in one direction, and means to vary the effective force of said turning means at different points of the travel of said cross carriage. 95
- 30 25. In a calculating machine, the combination of a cross decimal carriage, a hook mounted thereon, means to give the hook a tendency to rotate in one direction, and an auxiliary spring device also effective to give said hook a tendency to rotate, said auxiliary device varying its force at different points in the travel of said cross carriage. 100
- 35 26. In a calculating machine, the combination of a main carriage, a tabulating device for said main carriage, means to prevent the rebound of said main carriage when the same is tabulated, a cross decimal carriage adapted to be intermittently connected to said main carriage, and means to prevent the rebound of said cross carriage when the same is tabulated through the intermediation of said main carriage. 105
- 40 27. In a calculating machine, the combination of a main carriage, a tabulating device for said main carriage, a pawl and ratchet arrangement to prevent the rebound of said main carriage when tabulated, a series of connecting locations on said main carriage, a cross decimal carriage, means to connect said cross decimal carriage intermittently to said main carriage, said means consisting of a hook mounted on said cross carriage adapted to engage with one portion of said connecting locations, and an auxiliary guard also mounted on said cross carriage and adapted to engage with another part of said connecting locations. 110
- 45 28. In a calculating machine, the combination of a cross decimal carriage, a hook mounted on said decimal carriage, a guard mounted on said decimal carriage, and a cam arranged to be effective on both said hook and said guard at one end of the travel of said decimal carriage and to be effective on said guard alone at the other end of the travel of said decimal carriage. 115
- 50 29. In a calculating machine, the combination of a traveling carriage, tabulating devices for said carriage, means to prevent rebound of said carriage when the same is tabulated, a cross decimal carriage, a series of vertical totalizers mounted on said main carriage, a hook mounted on said cross carriage and adapted to engage with said vertical totalizers and thereby move said cross carriage in synchronism, and a guard mounted on said cross carriage, and also adapted to engage said vertical totalizers to prevent the over-running of said cross decimal carriage when the same shall have been picked up by any of said vertical totalizers. 120
- 55 30. In a calculating machine, the combination of a moving carriage, a cross computing carriage adapted to be connected intermittently thereto, a series of connecting locations on said cross carriage, a hook mounted on said cross computing carriage, a cam device adapted to disconnect said hook at a predetermined point of the travel of said main carriage, and a slot to positively constrain the motion of said hook except when said cross computing carriage is in a normal position. 125
- 60 65

31. In a calculating machine, the combination of a cross computing carriage, a hook mounted thereon, a pin mounted in said hook, a slot constraining the motion of said pin, and a recess in one end of said slot whereby when at that point said hook may be given motion independent of that produced by the action of said slot on said pin.
32. In a calculating machine, the combination of a cross computing carriage, a hook mounted on said cross computing carriage, a main computing carriage, a series of connecting locations on said main carriage adapted to pick up said hook at predetermined points, a cam adapted to disconnect said hook from said connecting locations and positively constrain it during the travel of said machine during the period of connection of the two carriages, an adjustable stop on the cross computing carriage to determine the normal position of said carriage, and an adjustable recess in said slot whereby the said recess may be adjusted to correspond with the setting of said adjustable stop.
33. In a calculating machine, the combination of a main computing carriage, a cross computing carriage adapted to be intermittently connected thereto, a series of adjustable calculation cams on said main computing carriage to automatically control the calculation of the cross computing carriage, a set of numeral keys, a lock for said numeral keys, a set of adjustable locking cams on said main carriage operative upon said lock, and a series of connecting locations on said main carriage to determine the points of engagement of said cross carriage with said main carriage, said calculation cams, locking cams and connecting locations being mounted in a single structure so as to be simultaneously adjustable on said main carriage.
34. In a calculating machine, the combination of a main computing carriage, a series of vertical totalizers mounted on said main carriage, a cross computing carriage adapted to be intermittently connected thereto, a series of cams mounted on said totalizers to control automatically the calculation of the cross computing carriage, a set of numeral keys, a lock for said numeral keys, a set of locking cams operative on said lock and mounted on said vertical totalizers, and a series of connecting locations to determine the points of engagement of said cross and main carriages, said connecting locations being also mounted on said vertical totalizers, said totalizers being adjustable along said main carriage whereby the totalizers, calculating cams and connecting locations may all be adjusted by a single operation.
35. In a calculating machine, the combination of a cross computing totalizer, a set of numeral keys, a gear shift device to determine the action of said numeral keys on said cross totalizer, a universal member moved by any of said keys, a plurality of controls for said gear shift device, and means for preventing the operation of said universal member when any of said controls are displaced from their proper position.
36. In a calculating machine, the combination of a master wheel, a gear shift device, a plurality of controls for said gear shift device, a set of numeral keys, a universal member operated by any of said numeral keys and means operated by said universal member to prevent operation of any of said numeral keys when any of said controls are displaced from their proper position.
37. In a calculating machine, the combination of a gear shift device, a set of numeral keys, a plurality of controls for said gear shift device, the position of said gear shift device being determined by the joint action of said controls, a rod controlling the position of said gear shift device, a series of slots in said rod, and a cam operated by said universal member to enter said slots and aline the gear shift device in its proper position upon the actuation of any numeral key.
38. In a calculating machine, the combination of a gear shift device, a set of numeral keys, a plurality of controls for said gear shift device, the position of said gear shift device being determined by the joint action of said controls, a rod controlling the position of said gear shift device, a series of slots in said rod, and a cam operated by said universal member to enter said slots and aline the gear shift device in a predetermined position on the operation of any numeral key.
39. In a calculating machine, the combination of a set of numeral keys, an actuating mechanism, a gear shift device determining the action of the keys on said actuating mechanism, a rod to control the position of said gear shift device, a plurality of controls operative on said rod, the position of said rod being determined by the joint action of said controls, a universal member operated by any of said keys, and a series of slots in said rod, said slots being so placed as to aline with said universal member when the gear shift device is in a proper position for operation.
40. In a calculating machine, the combination of a gear shift device, a rod controlling the position of said device, a floating lever determining the position of said rod, a plurality of controls operative upon said floating lever, a set of numeral keys, a universal member adapted to be operated by any of said numeral keys, and a series of slots in said rod adapted to be engaged by said universal member.

41. In a calculating machine, the combination of a cross decimal carriage, a spring tending to hold the same in a normal position, an adjustable stop determining the 5 normal position of said cross carriage, a hook mounted on said carriage, a slot to control the position of said hook, and a recess in said slot, said recess being adjustable to conform to said adjustable stop determining 10 the normal position of said cross carriage.

42. In a calculating machine, the combination of a cross decimal carriage, a spring holding the same in a normal position, an 15 adjustable stop having graduations thereon determining the normal position of said cross carriage, a hook mounted on said carriage, a pin on said hook, a slot to control the position of said pin, the lower part of 20 said slot being an adjustable plate having a recess therein, and having graduations thereon to conform to the graduations on said adjustable stop.

43. In a calculating machine, the combination of a cross computing carriage, a hook mounted thereon, a pin mounted in said hook, a plate mounted in the frame work having a surface constraining the rotation 25 of said hook in one direction, and an adjustable plate to constrain the motion of said hook in a contrary direction, said plate

having a recess therein to allow independent movement of said hook when said pin is in said recess.

44. In a calculating machine, the combination of a cross decimal carriage, a set of 35 keys, a universal member moved by any of said keys, a lever engaged by said cross carriage when in its normal position, and a lock for said universal member controlled by the 40 position of said lever.

45. In a calculating machine, the combination of a main carriage, a cross decimal carriage, a spring tending to return said 45 cross decimal carriage to its normal position, and a latch operating independent of the position of said main carriage and adapted to hold said cross carriage displaced from its normal position.

46. In a calculating machine, the combination of a main carriage, a cross decimal carriage adapted to be connected intermittently thereto, a spring tending to hold said cross carriage in its normal position, and a latch to hold said carriage out of its normal 50 position and in a position in which it will not be engaged by said main carriage.

In witness whereof, I have hereunto signed my name, this thirteenth day of March, 1916.

JOHN C. WAHL.
